UNITED STATES PATENT OFFICE.

AUGUSTUS BOWSER, DECEASED, LATE OF FORT WAYNE, INDIANA; BY COITE H. BOLENS AND CHARLES S. FAIR, ADMINISTRATORS, OF FORT WAYNE, INDIANA.

LIQUID-DISPENSING APPARATUS.

Application filed January 25, 1921. Serial No. 439,683.

To all whom it may concern:

Be it known that AUGUSTUS BOWSER, late a citizen of the United States, and resident of Fort Wayne, county of Allen, State of

5 Indiana, has invented a new and useful Improvement in Liquid-Dispensing Apparatus, of which the following is a specification.

This invention relates to liquid dispensing apparatus, and constitutes an improvement 10 on certain features of a device of the kind disclosed in the present inventor's prior Patent, No. 1,316,557, September 23, 1919. It relates particularly to the means for controlling the supply of air pressure which 15 forces liquid from a tank into a measuring head or reservoir to be delivered to a customer, and to means for disposing of the exhaust. It also includes a new system of piping in the stand which supports the 20 delivery reservoir with a novel, efficient, and easily accessible structure and arrangement of the valve control mechanism for the system. While it makes use of a valve somewhat similar to that in application Serial 25 No. 321,686, Sept. 4, 1919, the structural combination is different.

In the drawings:

Figure 1 is a diagrammatic view of the 30 general arrangement of the parts showing a small portion of the delivery stand in section.

Figure 2 is a side view of a portion of the stand, partly in section, showing the valve arrangement therein.

35 Figure 3 is an enlarged vertical section of the bottom plate of the head or glass measuring container.

Figure 4 is a bottom view of the plate shown in Figure 3.

40 Figure 5 is a longitudinal vertical section through the valve construction for controlling the air pressure and exhaust.

Figure 6 is a cross section through the stand on the line 6—6 of Figure 1 showing 45 the pipe arrangement therein; and

Figure 7 is a horizontal section through that portion of the valve casing which is shown at the right in Figure 5.

50 Since applicant's prior patent above noted fully discloses all of the detailed mechanism used in a system of the kind to which the present invention may be applied, it is not necessary to show and describe those features of such system as will be understood by those skilled in the art, and therefore

the drawing and description here are confined to those parts relating to the present improvement.

In Figure 1 there is shown a main supply tank or reservoir 10 for liquid such as gasoline and it may of course be placed in any convenient relation to the other parts of the system. It is provided with a pipe 11 extending upwardly therefrom to a point 12 convenient for filling and is also provided with a vent pipe 13 leading out to any convenient place. An auxiliary tank 14 is arranged at a lower level than the reservoir 10 and is connected to the reservoir 10 by an outlet pipe 15 leading from the bottom of the reservoir 10 out through the top through a cross pipe 16 and down to the auxiliary tank by pipe 17. The pipe 15 has in its lower end a check valve 18, and the arrangement is such that liquid is automatically supplied from the reservoir 10 to the tank 14 by siphon action. In order to prime the siphon when the storage tank 10 is first filled a priming pipe P connects with the siphon at its highest point, and is closed by a cap or plug P'. The tank 14 is also provided with a blowoff pipe B normally closed by a cap or plug B' and through which water and sediment can be blown out of the tank. The pipe 17 is connected to a supply pipe 19 adapted to convey the liquid from the tank 14 up to the stand for delivery to a customer. It passes up through the stand 20 and is connected at 21 to the bottom plate 22 of the graduated glass reservoir or container 23, which, as shown, is smaller than the tank 14. The supply pipe 19 is provided with a check valve c between its connection to pipes 16 and 17 and the bypass connection 27, later described. This check valve permits the liquid to pass up to the container 23 but prevents its flowing downward in the pipe and thus prevents air entering through the container 23 and pipe 19. The glass container 23 has an overflow pipe 24 open at its top and terminating at the proper distance from the top of the container fixed on as the maximum to which the container should be filled, and it is connected to the bottom plate 22 of the container at 25, and there is an overflow pipe 26 leading from that connection down through the stand and to the main reservoir 10. Within the housing 20 there is a by-pass connection 27 between the supply pipe 19

and the overflow pipe 26 with a valve 28 controlled by the longitudinal movement of the pin 29 to connect or disconnect the two pipes at that point, the purpose of connecting them being to permit, when desired, surplus oil remaining in the container below the level of the overflow outlet to return or drain back into the main reservoir 10. The controlling pin 29 passes through a face 30 of the casing, and the hinged cover plate 31 for that casing when moved into closed position will press on the end of the pin and thus open the connection between the pipes at that point, draining the container 23 automatically if this has not been done by the operator before closing the cover plate. The usual hose connection 32 leads from the socket 33 in the bottom plate 22 of the container 23 to convey the liquid in 20 that container to the point desired in delivering it to a customer.

The means for causing air pressure on the liquid in the auxiliary tank 14 to force it up to the receiver 23 consists of an air pipe 34 leading from any suitable source of air pressure and passing up the stand 20 and connected at its upper end to valve casing 35 at the socket 36 illustrated in Figure 5. A second air pipe 37 is connected to 30 the valve casing 35 at 38, and leads back down the stand and to the auxiliary tank 14. In addition to the air inlet and the air outlet pipes connected to the valve casing 35 there is an exhaust pipe 39 connected to this casing at 40, and leading down into the main reservoir 10.

The valve casing 35 has extending inward from one end a chamber 41 which is of uniform cross section and preferably cylindrical, and there is a contracted extension of this chamber at 42. In line with the first mentioned chamber and at the other end of the casing there is an enlarged chamber 43 with which the air inlet pipe 34 connects. This chamber 43 has surrounding the contracted portion 42 a valve seat 44. It will be noted that the connection 40 of the exhaust pipe enters the chamber 41 near its outer end and the connection 38 for the air pipe 37 communicates with this chamber 41 at 45 in advance of the connection between that chamber and the connection 40. A valve member comprising an outer portion 46 of uniform cross section fitting the chamber 41 is adapted to move longitudinally within that chamber and has a central reduced rod extension 47 extending through the contracted portion 42 and carrying on its end a valve 48 in the chamber 43 and adapted when moved to the right as shown in Figure 5 to fit the valve seat 44 and close communication between the chambers. There is a coil spring 49 in chamber 43 bearing at one end on the valve 48 and at the other end against the screw

threaded closure 50 and serving to normally hold the valve member in the position shown in Figure 5 with the inlet for compressed air shut. It will be observed that when the valve member is in this position the outlet 70 air pipe 37 and the exhaust pipe 39 are in communication and the effect of this is that any air pressure in the auxiliary tank 14 may be relieved through this valve casing and the connected pipes passing out to 75 the main storage reservoir 10. A movement of the valve member 46 inward will serve to cut off connection to the exhaust pipe 39 and at the same time open valve 48, thus bringing the air inlet pipe 34 into open connection to the air outlet pipe 37, thus causing the air pressure to operate on the liquid in the auxiliary tank 14 forcing it up to the delivery container 23. To fill that container, therefore, the operator simply presses on 80 the valve member 46 until the required amount of liquid appears in the visible container 23, and on releasing that pressure on the valve member it automatically returns to the position shown in Figure 5, cutting 85 off the air supply and permitting the compressed air in the auxiliary tank to pass through the exhaust to the main tank. This disposition of the exhaust air reduces the 90 explosion and fire hazard inasmuch as some 95 of the gasoline vapor carried along with the air may settle out in the large tank 10 and the vent pipe 13 having its outlet at a remote point from the apparatus thus removes the air with whatever vapor may be 100 left in it to a safe distance. Furthermore 105 gasoline vapor that settles out in the large tank 10 is saved. If the exhaust air were delivered immediately into the atmosphere, the vapor recovered in the tank 10 by condensation and otherwise would be lost. It 110 is to be noted that the valve construction for controlling the operation and connection of the parts is very simple and easy to operate and contains no parts likely to get 115 out of order. The closure 31 on the stand, while it covers and protects the valve member 46 against unauthorized operation when closed, does not contact with that member or move it to turn on the air pressure.

The operation of the device is as follows. After the tank 10 is first filled gasoline is poured into the priming pipe P until the latter is filled. This fills the tank 14, the legs 15 and 17 of the siphon, drives the air out through the check valve c, and fills the supply pipe 19 to above the level of this valve. The cap P' is then closed and made air tight, sealing the siphon and after gasoline has been forced out of 14, the siphon 125 will operate to fill it.

The first operation in supplying a customer is to so move the valve in the valve casing 35 as to connect air pipe 34 which is supplied with compressed air to air pipe 37 130

extending down to auxiliary tank 14, thus subjecting the liquid in that tank to pressure which forces it up through supply pipe 19 into container 23. This pressure cannot 5 force the liquid back into tank 10 because of the check valve at the lower end of pipe 15 and it is thus forced to pass up through supply pipe 19. When a sufficient supply is in reservoir 23, the air control valve in 10 casing 35 is so moved as to cut off the supply of air under pressure to pipe 37 leading to tank 14 and at the same time connect that pipe to exhaust pipe 39 whereby the liquid in the tank is relieved of the air pressure 15 and the air which had accumulated in tank 14 in forcing the liquid out may freely escape through pipe 37 and exhaust pipe 39. During this absence of pressure in tank 14 and while the air therein is escaping, the 20 liquid in supply pipe 19 would normally and naturally flow back into tank 14 taking the place of the escaping air and its level would pass below the top of pipe 17 where it joins pipe 16 and would thus destroy or 25 break the siphon connection between tanks 10 and 14 but the check valve in supply pipe 19 prevents this and this maintains the siphon connection in operative condition. The pipe 17 extending to a lower level than 30 pipe 15 the weight of the column of liquid in it overbalances that in pipe 15 and thus the necessary liquid to take the place of the escaping air in tank 14 automatically passes from tank 10 to tank 14 and quickly fills it 35 ready for the next operation. The siphon connection is thus always full ready for operation. It is believed that the operation by which the reservoir 23 is drained and the contents returned to tank 10 through the 40 upper portion of supply pipe 19 above the by-pass then through the by-pass and down overflow pipe 26 when the by-pass valve is opened will be clear from what has heretofore been said without further description. 45 It will be seen from what has been said above and upon inspection of Figures 1 and 6, that all of the piping for the supply of liquid to the graduated dispensing reservoir, for the overflow and return of any surplus supply and for draining the dispensing reservoir after a customer has been served, as well as the piping for the compressed air to cause pressure on a liquid in a distant concealed tank forcing a supply up to the 55 dispensing reservoir, and for exhausting the air pressure from said tank after the dispensing reservoir is filled, and conveying the exhaust vapor laden air to a distant point through a main liquid reservoir, all pass 60 up within the vertical hollow housing 20 which constitutes the stand for the dispensing reservoir in a very convenient and easily made and efficient parallel arrangement, and that the control mechanism is all located

at a single point accessible through a single 65 closure for the housing and is so constructed as to make the operation easy and certain. The inlet pipe 19 for supplying liquid to this delivery reservoir 23, and the overflow and drain pipe 26 are parallel but spaced 70 apart, leaving room between them for the transversely extending valve casing 35 which in turn has connected to it on its lower side the three parallel pipes 34 for the air pressure from an outside source, 37 for 75 the air pressure passing to the supply tank 14, and the air exhaust pipe 39 leading to the main liquid reservoir 10. The by-pass valve 27 connecting the pipes 19 and 26 is immediately above the valve casing 35 and 80 has operating means parallel to and immediately above the operating means for the air pressure and exhaust valve in casing 35, and both are adapted to be protected by the single closure 31. The structural arrangement is thus easy to make, neat in appearance, efficient in its action, easy to operate, and protects the piping from exposure and the apparatus from unauthorized tampering. It will be noted that the stand 20 constitutes not merely a support for reservoir 23, but an enclosed housing circular in cross section for the piping and valve control mechanism. 85

Having thus described the invention, what 90 is claimed as new and desired to be secured by Letters Patent is:

Dispensing apparatus of the class described, including in combination a reservoir, an auxiliary tank and an automatic 100 siphon construction for supplying the latter from the former, a dispensing head including a stand, a supply pipe leading up within said stand connecting said auxiliary tank and head, means for alternately supplying air pressure to the liquid in said auxiliary tank to force it up to said head and releasing said pressure and allowing it to exhaust through said reservoir, comprising 105 a valve casing in said stand, an air inlet pipe extending up within said stand connected thereto at one end, an air outlet pipe leading down said stand to said auxiliary tank connected thereto at the other end, an exhaust pipe connected thereto at a third 110 point near said air inlet connection and leading to said reservoir, and a longitudinally movable valve in said casing normally leaving said air outlet and exhaust pipe in communication but when operated by a longitudinal movement closing that communication and connecting the air inlet and outlet pipes. 115
